UNITED STATES PATENT OFFICE.

ALFRED COPONY, OF MOUNT CLEMENS, MICHIGAN, ASSIGNOR OF ONE-SIXTH TO THEODORE W. SWIFT AND ONE-SIXTH TO LELAND M. SWIFT, BOTH OF DETROIT, MICHIGAN.

GRAIN DOOR.

Application filed February 26, 1923. Serial No. 621,411.

To all whom it may concern:

Be it known that I, ALFRED COPONY, a citizen of the Austrian Republic, residing at Mount Clemens, in the county of Macomb 5 and State of Michigan, have invented certain new and useful Improvements in Grain Doors, of which the following is a specification, reference being had therein to the accompanying drawings.

10 This invention relates to grain doors and refers more particularly to grain doors such as are adapted for use in freight cars or other common carriers.

15 Among the objects of the invention are to provide an improved grain door of the character above referred to, which can be more economically constructed than those now in use; to provide in effect a truss bracing; to provide an improved grain door that 20 will prevent the spilling or leaking out of the grain; to prevent bulging of the grain door and possible binding of the regular car door. The invention also resides in the novel feature of adjustment whereby the 25 door can be used with car door openings of different widths which will provide a space between the top of the grain door and the car roof for filling the car. Still other features of the invention are the novel arrangement 30 for saving in the cost of lumber or other material, the improved arrangement for attaching and detaching the door from the car and in such further features of construction and combination of parts as will 35 more fully hereinafter appear.

In the drawings:

Figure 1 is a top plan view of a grain door embodying my invention;

40 Figure 2 is a side elevational view of the construction shown in Figure 1;

Figure 3 is a section on the line 3—3 of Figure 2.

45 Describing first in detail the particular embodiment of my invention shown in Figures 1, 2 and 3, A designates the side of a freight car having the inner wall A' and the outer wall A² secured at the door openings B to the door post B'. For closing the door opening B there is the regular 50 sliding door C which in its closed position slides completely across the door opening B. However, where grain is handled in freight cars, it is customary to provide a supplemental door known as a grain door.

Heretofore there has mainly been employed 55 for this purpose heavy boards nailed or otherwise secured to the door posts. This not only results in the waste of lumber but requires much heavier boards than is necessary with the present novel construction 60 of grain door. As shown in Figures 1, 2 and 3, the grain door D is formed in two sections D' and D² which are hinged together at B³ by suitable hinges B⁴. At the hinged joint between the door sections D' 65 and D² I preferably employ a canvas guard E which is looped back unto itself at E' so as to permit the angular position of the two sections D and D' with reference to each other to be shifted without, however, permitting the grain to leak out through the joint. Each of these door sections D' and D² is preferably made up of superimposed 70 portions D³ and D⁴ which in practice forms a plurality of door sections hinged together 75 as above set out to form the grain door proper and which are also provided with a canvas strip D⁵ protecting the joints between the two portions, the portions themselves being preferably built up of boards 80 tongued and glued into each other as shown in Figure 3 and at the lower end of the portion D³ there is a canvas strip E⁵ so that when the door is in use leakage of grain past any of the joints of the door is prevented. 85

At the free ends of each of the sections D' and D² there is a cleat or nailing strip E⁶ which abuts against the inner face of the door post B' and when nailed will hold the 90 grain door fixedly in position. In the novel arrangement just disclosed it will be noticed that the sections D, D' and D² form in relation to each other an angle bracing or truss which construction will give much greater 95 strength with lighter thickness of boards than is possible with the old construction. It will be noticed that the boards of the door sections D' and D² are bevelled at F so that when the cleats or nailing strips E 100 are fastened in position there is a comparatively tight joint formed between the grain door and the door post B'. A canvas strip E³ is also employed at this portion.

From the above description it will be 105 noted that the door can be readily adjusted to door openings of different widths and then quickly secured in place by simply nail-

ing the cleat or nailing strips E to the face of the door post. Also they can be readily removed when unloading and the sections D⁴ removed independently of the sections 5 D³. Since the apex of the triangle formed by the grain door is located inwardly of the side of the freight car, it will be spaced vertically away from the roof of the car at that point since in freight cars of standard construction the roof slants upwardly toward the center of the car as illustrated diagrammatically in Figure 3. This leaves a space for conveniently filling the car; in other words, permits the car to be filled at a 10 greater height than is possible through the old type doors wherein the boards were substantially in the plane of the wall of the car sides. Also by having the grain door extend inwardly in the form of an angle, 15 in case any small amount of grain leaks past the grain door, there will be a space between the grain door and the regular door of the freight car in which the grain can accumulate. In unloading the freight car it is only 20 necessary to pry a crowbar or suitable tool between the cleat E⁶ and the door post and to loosen the grain door from the freight car thus simplifying the removal of the 25 grain door and avoiding the removal of separate boards.

While I have shown and described my invention, the invention is not limited to the particular embodiment shown nor to the particular features of construction except 30 as ultimately set forth in the claims.

What I claim as my invention is:

1. A grain door adapted to form a truss 40 brace for use in freight cars or the like, comprising a plurality of sections hinged to each other at their inner ends, the outer ends of said sections having attached strips

adapted to abut against the door post or freight car, and rigidly secured thereto.

2. A grain door for use in freight cars or the like, comprising a plurality of sections hinged to each other at their inner ends and beveled at their outer ends and a strip attached to the outer ends of said sections for securing said door to the door post or freight car for preventing movement of the outer ends of said door when secured, thereby adapting said sections to form a truss brace when in use, said strips being removable from said door and door post or freight car to permit the movement 50 of said sections toward relative alignment.

3. A grain door for use in freight cars or the like, comprising a plurality of sections hinged to each other at their inner ends and beveled at their outer ends, a removable strip attached to the outer ends of said sections for securing said door to the door-post or freight car for preventing movement of the outer ends of said door when secured, thereby adapting said door to form 60 a truss base, and for permitting the sections of said door to move toward relative alignment when removed.

4. A grain door for use in freight cars or the like, comprising a plurality of sections hinged to each other at their inner ends, a strip attached to the outer ends of said sections for forming an abutment with the door post and for securing said door to said door post to form a truss brace, 70 said strip being removable from said door and door post to permit the enlargement 75 of the angle between said sections.

In testimony whereof I affix my signature.

ALFRED COPONY.
